ELECTRICALLY POWERED CAN OPENER

Barry L. Smith, Overland, and George A. Lehmann, Ferguson, Mo., assignors to The Dazey Corporation, St. Louis, Mo., a corporation of Missouri

Application February 18, 1957, Serial No. 640,781

16 Claims. (Cl. 30—4)

This invention relates generally to a can opening machine, and more particularly to improvements in an electrically powered can opener.

It is a major objective of the present invention to realize a can opener in which the mechanism for moving the feeding wheel into and out of operative relation to the cutting element, and the mechanism for rotating the feeding wheel during can opening operation is fully automatic and operable by closing a switch to actuate a power means.

Another important object is realized by the provision of a revolvable means on the can opener body that serves to move the feeding wheel eccentrically in and out of operative position relative to the cutting element, by the attachment of the feeding wheel to the power unit by an interconnecting shaft, and by the support of the power unit by the revolvable means such that the power unit will be raised and lowered upon actuation of the revolvable means.

Still another important object is achieved by a drive connection between the power unit and the revolvable means that maintains operative connection while the power unit is raised and lowered.

Other important advantages are realized by the provision of intermittent drive means in the above mentioned drive connection between the power unit and revolvable means which provides an intermittent rotation of the revolvable means in moving the feeding wheel into and out of operative relation to the cutting element.

Yet another important object is realized by a guide means between the power unit and a bracket attached to the can opener body which cooperates with the particular mounting of the power unit on the revolvable means to facilitate up and down movement of the power unit.

Another important object is realized by the provision of a movable platform to support the can during lid removal operation, and by the provision of means to raise and lower the platform selectively incident to moving the can into operative relation to the cutting and feeding elements.

Another important object is realized by the provision of a powered can opening machine that is durable in construction and capable of heavy duty operation, economical in manufacture, and which can be readily manipulated to open cans of various sizes up to a predetermined size limit.

The foregoing and numerous other objects and advantages of the invention will more clearly appear from the following detailed description of a preferred embodiment, particularly when considered in connection with the accompanying drawing, in which:

Fig. 1 is a top plan view of the can opening machine;

Fig. 2 is a side elevational view of the can opening machine shown in Fig. 1 with a portion of the driving and feeding mechanism cut away and shown in cross section, and

Fig. 3 is a fragmentary view of the drive connection, partly in cross section, as seen along line 3—3 of Fig. 2.

2

Referring now by characters of reference to the drawing, the various parts which constitute the operating mechanism of the can opening machine are mounted on a head member 10, preferably a metal casting, which member is rigidly secured to the upper end of a square sectioned tubular column 11. A suitable base and support assembly (not shown) is attached to the lower end of column 11 which can be clamped or fixed by other suitable means to a table or other horizontal support.

Describing now the operating head and particularly the can driving and feeding mechanism, the head member 10 has a horizontal bore in which is journaled a revolvable eccentric means including a bearing cylinder 12 (Fig. 2). Cylinder 12 has an eccentric bore lined by a bearing sleeve 13 in which is journaled a feed wheel shaft 14. A washer 15 of greater diameter than the bearing cylinder 13 seats against the forward end face thereof, the washer 15 being provided with an opening to accommodate the threaded end portion of the shaft 14, on which portion is mounted a peripherally toothed feeding wheel 16. The outer face of feeding wheel 16 lies substantially flush with the vertical front surface of subjacent shoulder 17 formed integrally on head member 10, and with the front surface of column 11. Formed integrally with the rear end of bearing cylinder 12 is an annular flange 20 that bears against the rear face of head member 10.

The cutting wheel 21 (Fig. 2) has opposite sides which converge to a sharp cutting edge. An integral collar or neck portion 22 projects axially from the inner side of the wheel and abuts the outer end face of a plunger member (not shown) to which the cutting wheel 21 is rotatively attached by means of an axle stud 23. The particular mounting of cutting wheel 21 and the adjustable means for determining the operative position of the cutting wheel relative to the feeding wheel 16 is or may be identical with the assembly shown by U. S. Patent No. 2,361,561 issued October 31, 1944 to W. F. Mueller, et al. In Fig. 1, a plug 24 attached to head member 10 forms a closure for the rear end of a plunger bore and constitutes an adjustable abutment. As explained fully in the above mentioned patent, the normal spacing of the cutting wheel 21 with respect to the feeding wheel 16 is determined by the position of abutment plug 24 which may be rotatively adjusted.

The relative spacing of cutting wheel 21 and feeding wheel 16 is of importance when these members are cooperating to open a can. If the space is too great an irregular ragged cut results, and the flange of the can is apt to slip through the space, thus causing the can to become detached from the operating members of the machine. When the inner face of cutting wheel 21 is too close to the outer face of feeding wheel 16 the cutting wheel 21 tends to shear or shave particles of metal from the can flange, which particles generally and undesirably find their way into the contents of the can. A satisfactory spacing of these members has been found to be approximately twice the thickness of the can metal.

To assure a driving traction of feeding wheel 16 on the rim of the can, there is provided a pair of vertically yieldable pressure feet 25 arranged to bear downwardly on the can rim at points circumferentially before and behind cutting wheel 21. These pressure feet 25 consist of L-shaped members secured by rivets 26 to a movable housing plate 27. The particular mounting of housing plate 27 is described in detail in the above mentioned Mueller Patent No. 2,361,561.

Attached to column 11 by a coacting bolt and wing nut 30 is a bracket structure 31 including a substantially horizontally disposed platform 32 extending rearwardly of column 11.

The power unit consists of an electrical motor 33 the

housing of which is fastened to the casing of a speed reducing gear unit 34. The speed reducing unit 34 and motor 33 constitute a power means for automatically rotating feeding wheel 16 as will be later described.

The motor 33 and reduction unit 34 constituting a unitary structure is mounted on an L-shaped bracket 35. A resilient means is used to mount the power means 33-34 to horizontal bracket portion 36. As is best shown in Fig. 2, the resilient means includes a rubber grommet 37 fixed to bracket portion 36 and a T-shaped washer element 40 extending upwardly through the grommet 37. A screw element 41 extends upwardly through washer 40 and grommet 37 and is fixed to the speed-reducing unit 34, the screw element 41 thus securely fastening the power means 34-33 to the resilient grommet 37.

The feeding wheel shaft 14 extends rearwardly of bearing cylinder 12 and is connected to the gear operated speed-reducing unit 34, the shaft 14 being journaled in vertical bracket portion 42 immediately adjacent the reduction unit 34.

A guide means is provided between bracket 35 and platform 32 to assist in the movement of the power unit 33-34 incident to can opening operation. The guide means consists of a pair of post elements 43 fixed to bracket portion 36. A pair of cooperating socket structures are provided in platform 32 consisting of apertures provided with bearing sleeves 44. The post elements 43 extend through bearing sleeves 44 and project below platform 32. The lower ends of post elements 43 are provided with head portions 45 to prevent accidental or unintentional withdrawal of post elements 43 from the cooperating bearing sockets 44.

A drive connection is provided between the power unit 33-34 and the revolvable bearing cylinder 12. This drive connection includes a drive gear 46 fixed to feeding wheel shaft 14 and rotatable therewith, and a driven gear 47 fixed to the revolvable bearing cylinder 12 and revolvable therewith. An interconnecting means for gears 46 and 47 is carried by the L-shaped support bracket 35. The interconnecting means includes a stub shaft 50 fixed to vertical bracket portion 42 and extending forwardly below gears 46-47. Rotatively mounted on stub shaft 50 is a gear 51 that meshes with drive gear 46. Rotatable with gear 51 is an interrupted-tooth gear 53 that intermittently enmeshes with driven gear 47. It will be apparent that gears 51 and 53 rotate as a unit on stub shaft 50, the gears being attached by connecting sleeve 52.

A second bracket 54 is attached to column 11 and extends forwardly of the column below the cutting and feeding elements. Mounted on bracket 54 is a movable platform 55 including a center post 56 depending through a compatible socket 57 formed in bracket 54. The mounting of post 56 in socket 57 enables rotation of platform 55 in addition to a raising and lowering movement.

Attached by screws 61 to the under side of bracket 54 is a pair of lugs 60 spaced on opposite sides of center post 56 of the platform 55.

A shaft 62 extends transversely of and is journaled for rotation in lugs 60, the shaft 62 extending laterally outwardly as is more clearly shown in Fig. 1. Attached to the outermost free end is a wheel 63 which can be manually manipulated to raise and lower platform 55 as will be described. Fixed to shaft 62 and located between lugs 60 immediately below the lower end of center post 56 is an eccentric cam 64. Rotation of shaft 62 causes engagement of the camming surface of cam 64 with center post 56, the cam causing a raising or lowering of such platform.

A curvilinear plate structure 65 is attached to the bracket 54 and cooperates with the platform 55 to maintain the can shown in dotted lines at 66 in proper position on platform 55. In addition, it will be noted that platform 55 is slanted slightly from the horizontal so that the upper end of the can 66 is tilted toward the can

opener body, thus assuring that the upper rim will be moved into operative position relative to cutting and feeding wheels 16-21 when the can 66 is raised on platform 55.

It is thought that the operation and functional advantages of the can opening machine have become fully apparent from the foregoing detailed description of parts, but for completeness of disclosure, a step by step account of the lid-removing procedure is hereinafter set forth.

First, the can 66 to be opened is placed on platform 55, and wheel 63 is manually turned so that cam 64 engages the lower end of post 56 and raised platform 55 and can 66 upon rotation of shaft 62. The can 66 is moved upwardly into operative position relative to the cutting wheel 21. It will be noted at this point that in the at-rest position of the mechanism the bearing cylinder 12 is disposed so that the feeding wheel 16 is located in its inoperative position, or in other words in its lowermost position.

When can 66 is located in cutting position, the power unit is energized by closing a switch 67, the motor 33 acting through speed reduction unit 34 to rotate feeding wheel shaft 14. As shaft 14 rotates the drive gear 46 meshes with gear 51 which drives interrupted tooth gear 53. The mutilated gear 53 meshes with driven gear 47 and causes a rotation of bearing cylinder 12 so that the feeding wheel 16 is raised to its cutting position. When the feeding wheel is raised to this operating position, the mutilated gear 53 will operatively disengage from driven gear 47, and hence permit feeding wheel 16 to be maintained in this operating position for a predetermined length of time. Simultaneously, the feeding wheel 16 is rotated by shaft 14 and causes rotation of can 66 incident to removal of the lid by cutting wheel 21.

The machine is adapted to cut lids from cans of various sizes up to a predetermined size limit, such limit being dependent on the number of revolutions of the feeding wheel 16 while the mutilated gear 53 is operatively disengaged from the driven gear 47. The gears 53 and 47 must be disengaged for a sufficient period to permit feeding wheel 16 to rotate the can 66 at least one complete revolution.

After the lid has been removed, the mutilated gear 53 will again operatively mesh with driven gear 47 and cause further rotation of bearing cylinder 12, and hence cause eccentric movement of feeding wheel 16 to its inoperative or lower position. When the feeding wheel 16 is located in this inoperative position the power unit is deenergized by opening of the operating switch 67. Upon deenergization, the feeding wheel 16 will stop rotating and the bearing cylinder 12 will be located so that the feeding wheel 16 will be located in its lowermost position ready for the next can opening operation.

Then, the wheel 63 may be rotated so that the cam 64 will permit lowering of platform 55, and hence allow removal of the can 66.

It will be particularly noted that during this can opening operation while the bearing cylinder 12 is rotated, the entire power unit including the drive connections will be raised and lowered therewith since this structure is supported by the revolvable means. During this raising and lowering movement of the power unit, the guide means constituted by posts 43 and sockets 44 will guide the power unit during such movement. Since the interconnecting means of gears 51 and 53 is fixed to and carried by the supporting bracket member 35 of the power unit, an operative connection between the power unit and the revolvable means will be maintained at all times.

Although the invention has been described by making detailed reference to a single preferred embodiment, such detail is to be understood in an instructive, rather than in any restrictive sense, many variants being possible within the scope of the claims hereunto appended.

We claim as our invention:

1. A can opening machine comprising a body, a cutting element on said body, a feeding wheel rotatively mounted on said body, revolvable means on said body for permitting eccentric movement of the feeding wheel into and out of operative relation with said cutting element, a platform on said body, a power unit including a shaft connected to said feeding wheel for rotation of said wheel, and guide means between said power unit and said platform for permitting relative movement incident to such eccentric movement.

2. A can opening machine comprising a body, a cutting element on said body, a feeding wheel rotatively mounted on said body, revolvable means on said body for permitting eccentric movement of the feeding wheel into and out of operative relation with said cutting element, a platform on said body, and a power unit including a shaft connected to said feeding wheel for rotation of said wheel, the power unit being supported by said revolvable means.

3. The combination and arrangement of elements as set forth above in claim 2, but further characterized by the provision of drive means interconnecting the power unit and said revolvable means for eccentric movement of the feeding wheel.

4. A can opening machine comprising a body, a cutting element on said body, a feeding wheel rotatively mounted on said body, revolvable means on said body for permitting eccentric movement of the feeding wheel into and out of operative relation with said cutting element, a platform on said body, a power unit including a shaft connected to said feeding wheel for rotation of said wheel, the power unit being supported by said revolvable means, drive means interconnecting the power unit and said revolvable means for eccentric movement of said feeding wheel, and guide means between the power unit and said platform for assisting relative movement incident to such eccentric movement.

5. A can opening machine comprising a body, a cutting element on said body, a feeding wheel rotatively mounted on said body, revolvable means on said body for permitting eccentric movement of the feeding wheel into and out of operative relation with said cutting element, a platform on said body, a power unit including a shaft connected to said feeding wheel for rotation of said wheel, drive means interconnecting the power unit and said revolvable means for eccentric movement of said feeding wheel, a support member attached to said power unit, and guide means between the support member and said platform for permitting relative movement incident to such eccentric movement.

6. A can opening machine comprising a body, a cutting element on said body, a feeding wheel rotatively mounted on said body, revolvable means on said body for permitting eccentric movement of the feeding wheel into and out of operative relation with said cutting element, a platform on said body, a power unit including a shaft connected to said feeding wheel for rotation of said wheel, a drive connection between the power unit and said revolvable means including a drive element carried on and operated by the power unit and a driven element attached to the revolvable means, and guide means between the power unit and said platform for assisting relative movement incident to eccentric movement of the feeding wheel upon rotation of said revolvable means by said drive connection.

7. A can opening machine comprising a body, a cutting element on said body, a feeding wheel rotatively mounted on said body, revolvable means on said body for permitting eccentric movement of the feeding wheel into and out of operative relation with said cutting element, a platform on said body, a power unit including a shaft connected to said feeding wheel for rotation of said wheel, the power unit being supported by said revolvable means, a drive element connected to the power unit, a

driven element connected to said revolvable means, and means interconnecting the said drive and driven element so that said revolvable means is actuated upon actuation of the power unit, and guide means between said power unit and said platform for assisting relative raising and lowering movement of said power unit upon eccentric movement of the feeding wheel.

8. The combination and arrangement of elements as recited above in claim 7, but further characterized in 10 that the means interconnecting the said drive element and driven element is attached to and carried by the power unit so as to maintain operative connection between the power unit and revolvable means upon raising and lowering movement of said power unit.

9. A can opening machine comprising a body, a cutting element on said body, a feeding wheel rotatively mounted on said body, revolvable means on said body for permitting eccentric movement of the feeding wheel into and out of operative relation with said cutting element, 15 a platform on said body, a power unit including a shaft connected to said feeding wheel for rotation of said wheel, a drive connection between the power unit and the revolvable means including an interrupted tooth gear and a coacting gear intermittently meshing to provide an 20 intermittent rotation of the revolvable means, and guide means between said power unit and said platform for assisting relative raising and lowering movement of the power unit incident to the eccentric movement of said feeding wheel.

10. A can opening machine comprising a body, a cutting element on the body, a feeding wheel rotatively mounted on said body, a revolvable means on said body for permitting eccentric movement of the feeding wheel into and out of operative relation with said cutting element, 25 a platform on said body, a power unit including a shaft connected to said feeding wheel for rotation of said wheel, a drive element connected to the power unit, a driven gear fixed to the revolvable means, and means interconnecting the said drive element and said driven 30 gear including an interrupted tooth gear intermittently enmeshing with the driven gear to rotate intermittently the revolvable means, the interconnecting means being attached to and carried by the power unit, and guide means between said power unit and said platform for assisting relative movement incident to eccentric movement of the feeding wheel.

11. A can opening machine comprising a body, a cutting element on said body, a feeding wheel rotatively mounted on said body, revolvable means on said body for permitting eccentric movement of the feeding wheel into and out of operative relation with said cutting element, a platform on said body, a power unit including a shaft connected to said feeding wheel for rotation of said wheel, the power unit being supported by said revolvable means, a support member attached to said power unit, a 45 drive gear fixed to the shaft of said power unit, a driven gear fixed to the revolvable means, an interconnecting gear mechanism carried by the support member including a stub shaft, a gear rotatable on the stub shaft and meshing with the drive gear, an interrupted tooth gear on the stub shaft and rotatable with the other gear on said stub shaft, the interrupted tooth gear intermittently enmeshing with the driven gear to rotate intermittently the revolvable means, and guide means between the support member and platform for assisting relative raising and lowering movement of the power unit upon eccentric movement of the feeding wheel incident to rotation of the revolvable means.

12. A can opening machine comprising a body, a cutting element on said body, a feeding wheel rotatively mounted on said body, revolvable means on said body for permitting eccentric movement of the feeding wheel into and out of operative relation with said cutting element, a platform member on said body, a power unit including a shaft connected to said feeding wheel for rotation of said

wheel, the power unit being supported by said revolvable means, a support member attached to said power unit, slide elements carried by one of said members, the slide elements engaging the other said member to guide the power unit during raising and lowering movement upon rotation of said revolvable means.

13. The combination and arrangement of elements as recited above in claim 12, but further characterized by the provision of drive means interconnecting the power unit and said revolvable means for eccentric movement of said feeding wheel, the drive means including means carried by the support member to enable operable connection of the drive means with the power unit and revolvable means during raising and lowering of the power unit upon rotation of the revolvable means.

14. A can opening machine comprising a body, a cutting element on the body, a feeding wheel rotatively mounted on said body, revolvable means on said body for permitting eccentric movement of the feeding wheel into and out of operative relation with said cutting element, a platform member on said body, a power unit including a shaft connected to said feeding wheel for rotation of said wheel, drive means interconnecting the power unit and said revolvable means for eccentric movement of said feeding wheel, a support member attached to said power unit, post elements attached to one of said members, the other member being provided with apertures adapted to receive said post elements to guide the power unit during raising and lowering movement upon rotation of the revolvable means.

15. The combination and arrangement of elements as

recited above in claim 14, but further characterized in that the drive connection includes a pair of meshing gears one of which is provided with interrupted tooth formations to provide an intermittent rotation of the revolvable means.

16. A can opening machine comprising a body, a cutting element on said body, a feeding wheel rotatively mounted on said body, revolvable means on said body for permitting eccentric movement of the feeding wheel into and out of operative relation with said cutting element, a platform on said body, a power unit including a shaft connected to said feeding wheel for rotation of said wheel, the power unit being supported by said revolvable means, a support member attached to said power unit, a drive gear fixed to the power unit shaft, a driven gear fixed to the revolvable means, a gear assembly carried by said support member and including a stub shaft, a first gear on said shaft and meshing with the drive gear, an interrupted tooth gear on the stub shaft and rotatable with said first gear, the interrupted tooth gear enmeshing with the driven gear to provide an intermittent rotation of said revolvable means, post elements fixed to said support member, the platform being provided with apertured sockets to receive the post elements and guide the power unit during raising and lowering movement upon rotation of the revolvable means.
